UNITED STATES PATENT OFFICE.

GEORGE B. HOWARD, OF SOMERVILLE, MASSACHUSETTS.

FUSEE THROWER AND GUIDE.

SPECIFICATION forming part of Letters Patent No. 627,232, dated June 20, 1899.

Application filed January 19, 1899. Serial No. 702,657. (No model.)

To all whom it may concern:

Be it known that I, GEORGE B. HOWARD, of Somerville, in the county of Middlesex and State of Massachusetts, have invented certain 5 new and useful Improvements in Fusee Throwers and Guides, of which the following is a specification.

This invention has for its object to provide a simple and effective device for throwing and 10 guiding fusees from moving railway-trains in such manner that the fusee, which is provided at its lower end with a spur—will strike the surface at which it is thrown with the spur end in advance, thus providing with 15 reasonable certainty for the planting of the fusee in the desired position—that is, supported in a vertical position by the spur, so that the flame of the fusee will be directed upwardly and thus be seen to the best advan- 20 tage.

The fusee now in common use is a tube charged with suitable combustible material and having at one end a spur and at the other end an igniting device, which is usually a 25 part of a complete self-igniting compound, the other part of said compound being placed on the outer end of a cap or cover, which is applied to the fusee when it is not required for use. When the fusee is to be ignited, the 30 cap is removed, and the igniting material on its outer end is rubbed against the complementary material on the fusee, thus igniting the charge. The fusee is held in one hand of the operator during this operation and is 35 then thrown downwardly upon the railway-track, the trainman aiming as accurately as possible in the effort to cause the spur to penetrate the surface which it strikes.

Owing to the fact that the fusee ignites very 40 quickly and projects its flame to a considerable height the trainman is obliged to act very quickly and often to avoid being burned throws the fusee so hurriedly and inaccurately that it falls flat upon the ground, its flame 45 being thus obscured wholly or in part.

My invention, which is intended to enable the trainman to accurately and carefully throw the fusee without risk of being burned, 50 consists as a whole in a fusee thrower and guide open at one end and having at the other end a handle whereby the guide may be wielded and a stop to limit the entrance of

the fusee into the guide, the guide being of such length that a complementary igniting device and the fusee may be inserted and the 55 latter ignited within the guide and then forcibly thrown by giving the guide a downward swinging movement.

Of the accompanying drawings, forming a part of this specification, Figure 1 represents 60 a sectional view of an ordinary fusee. Fig. 2 represents a sectional view of my improved fusee thrower and guide, the fusee and its cap being shown in the position they occupy in the guide when the fusee is being ignited 65 and thrown. Fig. 3 represents a perspective view showing a fusee properly planted and in the act of discharging.

The same letters of reference indicate the 70 same parts in all the figures.

In the drawings, *a* represents a fusee which consists of a tubular body containing a charge of suitable combustible composition, said body having at one end a closing-plug provided with a spur *b* and at the other end a 75 cap provided with a core or plug of combustible material.

d represents a cap which is removably applied to the fusee in position to cover the combustible tip *c*, said cap having on the outer 80 surface of its outer end a coating *d'*, containing a chemical which when rubbed against the tip *c* will cause combustion, the tip *c* and the coating *d'* resembling the two parts which cause the combustion of a safety-match. 85

In carrying out my invention I provide a thrower or guide for the said fusee, which comprises a tube *f*, which is open at one end and is adapted to receive the fusee *a* and its cap *d* and is provided at its inner end with 90 a stop *f'* to limit the entrance of the fusee into the guide, the length of the guide between its open end and the stop *f'* being sufficient to receive the cap *d* and a considerable portion of the body of the fusee when 95 said parts are separated and arranged so that the surface *d'* of the cap is in contact with the tip *c* of the fusee, the spur end of the fusee projecting far enough to enable it to be grasped and rotated to cause sufficient 100 friction to ignite the tip *c* and the charge of the fusee. The stop *f'*, as here shown, is the end of a handle *f'*, which is preferably of wood and is inserted in one end of the tube *f*.

A contracted orifice f^2 extends through the handle to permit the entrance of air into the guide when the fusee is being thrown therefrom.

- 5 When a trainman wishes to plant a fusee, he removes the cap d from the fusee and places it in the tube or guide f with its coating d' outward and then inserts the fusee in the guide with its tip c next the coating d' , 10 the spur b projecting. He then, holding the handle f in one hand and grasping the projecting end of the fusee in the other, rotates one of said parts sufficiently to cause the ignition of the tip. He then by a quick 15 downward swinging movement of the guide throws the fusee from the guide and causes its spur b to penetrate the surface it strikes, as shown in Fig. 3.

The handle f' is preferably protected 20 against the heat generated within the guide by making it of a suitable material which is a non-conductor of heat, the handle being in this case made of wood. It is obvious, however, that any other suitable non-conducting 25 material may be used to protect the surface of the handle.

I do not limit myself to the employment of the air-admitting orifice f^2 , although the same is desirable, particularly when the fusee fits 30 the interior of the guide somewhat closely.

I claim—

1. The combination with a fusee and a cap therefor the outer ends of which are provided with complementary igniting means, of a fusee thrower and guide comprising a tube which 3 is open at one end and has an unobstructed inner surface along which the fusee is adapted to slide freely, and a handle affixed to the other end of the tube and composed of a material which is a non-conductor of heat, said 4 handle forming a stop to limit the entrance of the fusee into the guide, the length of the tube beyond the stop being less than the combined length of the fusee and its cap when the latter are inserted in the tube with their 4 outer ends in contact with each other.

2. A fusee thrower and guide comprising a metallic tube which is open at one end and has a smooth unobstructed interior, and a handle affixed to the other end of the tube and 5 composed of a material which is a non-conductor of heat, said handle having an unobstructed orifice extending through it for the admission of air to the guide while the fusee is being thrown.

In testimony whereof I have affixed my signature in presence of two witnesses.

GEORGE B. HOWARD.
